UNITED STATES PATENT OFFICE.

CHARLES L. CASSADY, OF RODEO, NEW MEXICO.

DISK-SHARPENER.

1,044,137.

Specification of Letters Patent.

Patented Nov. 12, 1912.

Application filed March 21, 1912. Serial No. 685,378.

To all whom it may concern:

Be it known that I, CHARLES L. CASSADY, a citizen of the United States, residing at Rodeo, in the county of Grant, State of New Mexico, have invented certain new and useful Improvements in Disk-Sharpener; and I do hereby declare the following to be a full, clear, and exact description of the invention, such as will enable others skilled 10 in the art to which it appertains to make and use the same.

This invention relates to disk sharpeners.

The object of the invention resides in the provision of a disk sharpener which can 15 be readily associated with a disk plow or a disk harrow so as to effect the sharpening of a disk while the machine is in motion and without requiring the removal of the disk or the least disorganization of the machine part to arrive at the result sought.

A further object of the invention resides in the provision of a disk sharpener of the character referred to in which the grinding element may be adjusted relatively to the 25 disk being sharpened so as to bear upon the latter with the proper force and in the proper relation.

With the above and other objects in view, the invention consists in the details of construction and in the arrangement and combination of parts to be hereinafter more 30 fully described and particularly pointed out in the appended claim.

In describing the invention in detail, reference will be had to the accompanying drawings wherein like characters of reference denote corresponding parts in the several views, and in which—

Figure 1 is a front elevation of a fragment of a disk plow showing the invention applied, Fig. 2, a side elevation of the sharpener on an enlarged scale, Fig. 3, a section on the line 3—3 of Fig. 2, Fig. 4, a section on the line 4—4 of Fig. 3, Fig. 5, 45 a detail perspective view of the supporting brackets of the sharpener, Fig. 6, a detail perspective view of the grinding element carrier supporting arm, and Fig. 7, a detail perspective view of the grinding element carrier.

Referring to the drawings A represents a cultivating disk and B the scraper supporting arm of a disk plow all of well known construction. Clamped to the arm B is a bracket 10 and adjustably connected to this bracket is the inner end of a grinding ele-

ment supporting arm 11. It will be noted that the bracket 10 is provided with a plurality of openings 12 while the inner end of the arm 11 is provided with a plurality of openings 13 certain of which latter are adapted to be brought into registration with the openings 12 to permit of the passage of bolts 14 therethrough and the securing of the arm 11 to the bracket 10 in different 60 adjustments. The outer end of the arm 11 is offset with respect to the inner end and this offset outer end is provided intermediate with spaced ears 15 between which is pivotally mounted a grinding element 65 carrier 16 which extends contiguous with the outer end of the arm 11. The outer face of the carrier 16 is grooved as at 17 and this groove is crossed at spaced points by bridges 18. Disposed in the groove 17 is 70 a grinding element 19 which is held against movement longitudinally of the carrier 16 by means of binding screws 20 mounted in the bridges 18 and manipulated to bind respectively upon the grinding element 19. 75 Mounted in the outer end of the offset portion of the arm 11 is an adjusting screw 21. Rotatably mounted on the inner end of each 80 adjusting screw 21 is a socket 22 which receives one end of a spring 23, the other 85 end of said spring bearing against the inner face of the carrier 16. By this construction it will be apparent that the outer end of the carrier 16 is yieldingly held against movement on its pivot toward the outer end 90 of the offset portion of the arm 11 by means of the spring 23. It will be further apparent that by manipulating the adjusting 95 screw 21 the tension of the spring 23 may be varied and the carrier thus disposed at different angles to the offset end of the arm 11 and of course in different adjustments with respect to the disk being sharpened. This adjustment just referred to will enable the grinding element 19 to be brought 100 into proper relation to a disk to effect the sharpening thereof.

Mounted in the inner end of the offset portion of the arm 11 is a set screw 24, the forward end of whose shank is adapted to 105 engage the inner end of the carrier 16 and act as a stop to limit the movement of the outer end of the carrier away from the outer end of the offset portion of the arm 11 under the influence of the spring 23. This 110 set screw 24 may be readily adjusted so as to vary the extent of movement of the outer

end of the carrier under the influence of the
spring 23.

What is claimed is:

A disk sharpener comprising a bracket
5 provided with means for attachment to a
plow part, an arm adjustably connected to
said bracket, ears on the sides of said arm
at corresponding points respectively, a
grinding element carrier pivotally mounted
10 between said ears, a grinding element sup-
ported by said carrier, an adjusting screw

mounted in the outer end of said arm, and
a spring having one end in engagement with
said adjusting screw and its other end in
engagement with the outer end of said car- 15
rier.

In testimony whereof, I affix my signa-
ture, in presence of two witnesses.

CHARLES L. CASSADY.
